UNITED STATES PATENT OFFICE.

WILLIAM B. MUNN, OF MEMPHIS, TENNESSEE, ASSIGNOR OF ONE-HALF TO MERRILL JACOBS, OF MEMPHIS, TENNESSEE.

CONVERTIBLE WORKTABLE.

Application filed May 16, 1922. Serial No. 561,326.

To all whom it may concern:

Be it known that I, WILLIAM B. MUNN, a citizen of the United States of America, residing at Memphis, in the county of Shelby and State of Tennessee, have invented certain new and useful Improvements in Convertible Worktables, of which the following is a specification.

My present invention relates to improvements in a convertible work table and contemplates combinations and arrangements of parts involving a convertible table upon which packages may be sorted and afterward wrapped, together with means for manipulating and cutting paper into sheets for wrappers for the sorted packages. While the subject matter of the invention is applicable for use in a variety of ways, I shall hereinafter refer to the machine as used for sorting and wrapping laundry packages, and in the drawings the invention is illustrated in connection with a sorting table such as is used in laundries. By the utilization of my invention both time and labor are saved because of the convenience afforded for sorting the laundry into packages and subsequently converting the machine or sorting table for use in feeding the wrapping paper, cutting the paper into sheets of the required size and finally wrapping the successive bundles or packages. To attain these ends the invention consists in certain novel combinations and arrangements of parts as will be hereinafter more fully pointed out and claimed.

In the accompanying drawings I have illustrated one complete example of the physical embodiment of my invention wherein the parts are combined and arranged according to the best mode I have so far devised for the practical application of the principles of my invention. The invention as illustrated exemplifies the parts in one form, but it will be understood that changes in the details of construction may be made in various parts of the machine within the scope of my appended claims without departing from the spirit of my invention.

Figure 1 is a detail view in front elevation of a portion of a sorting table having my invention applied thereto, the parts being shown in the position occupied while bundles or packages are being wrapped.

Figure 2 is a transverse vertical sectional view at line 2—2 of Figure 1.

Figure 3 is a perspective view of the table, complete, illustrated in Figures 1 and 2, with the parts in position for sorting laundry and inaking up packages.

Figure 4 is a side elevation of the paper cutter.

Figure 5 is a top plan view of the cutter of Fig. 4, parts of the cutter being removed for convenience of illustration.

Figure 6 is a transverse vertical sectional view of the cutter at line 6—6 of Figure 5, showing also the relation of the guide bar for the cutter.

Figure 7 is an enlarged detail view, partly in section showing the paper retaining means.

Figure 8 is a detail view, partly in section, showing one end of a paper retaining roller.

In the drawings I have illustrated the invention as applied to a usual type of sorting table 1 of rectangular shape and standing upon legs 2, but it will be understood that the table-top 1 may form part of other structures suitable for the purpose. The top 1 is provided with a removable panel 3 which is complementary to an opening 4 in the top, and ledges or shoulders 5 may be utilized to support the panel 3 which is preferably of wood. The panel 3 is adapted to be used alternately with a complementary panel 6, which may be of metal and form the top of a rectangular housing 7.

The panels are both adapted to lie flush with the top of the table when used, the panel 3 however being bodily removable and detachable from the table structure, while the panel 6 may be elevated above the top of the table but remains connected with the table structure. Thus in Figure 3 the panel 3 has been removed and the panel 6 is being utilized, as for instance in a laundry, where the clear and unobstructed table top is adapted for sorting the laundry articles into bundles preparatory to wrapping.

In Figures 1 and 2 the panel 6 has been elevated above the table top, and the panel 3 has been inserted in position in order that the sorted bundles may be wrapped, the entire surface of the table top being available for this use.

The panel 6 and housing 7 form a liftable head which is supported from a pair of spaced, vertical legs 8, 8, that pass through the opening 4 of the table top, and are connected at their lower ends by a cross bar 9 to form a rigid supporting frame for the liftable head. At the center of the bar 9 is attached a slideable head 10, standing in upright position, and movable 10 in vertical direction within the fixed hollow post 11, which is provided with guide flanges 11^a that retain the slide head and guide it in its movement as the liftable head and its supporting frame are raised or lowered. The guide post is rigidly supported from a base 12 affixed to a floor or other support, and at its upper end the post may be braced from the underside of the table as by diagonal braces 13. These parts may 15 be made up of suitable material for the purpose and constructed in proper sizes and shapes as desired, and the entire movable element comprising the liftable head, its frame, and the sliding head may be raised 20 or lowered by turning the handle wheel 14. A bracket 15 is attached beneath the table top in which is journaled the wheel-shaft 15' and a reel 16 on the shaft is revolved by the action of the wheel to wind or un- 25 wind the cord or cable 17 on the reel. The cord is passed from the reel and wrapped with one or two turns around a hook or other device 18 on the cross bar 9 and by friction the cord is held to the hook. The 30 cord thence passes up over a guide pulley 19 supported from the fixed post 11, and a counterbalancing weight 20 is attached at the free end of the cord. It will be evident that by turning the handle wheel the lift- 35 able head may be elevated to position of Figure 1, or by reverse movement of the wheel the liftable head may be lowered to position of Fig. 3, the counterbalancing weight and supporting cable 17 maintaining the equilibrium of the movable member 40 in all positions. The weight 20 counterbalances the load of the liftable panel and slideable head, so that the panel will remain balanced and stationary in its elevated 45 position, but may be moved as described by turning wheel 14. If necessary means may be employed to control the movement of the shaft 15'.

After the bundles have been sorted on the table in Figure 3, the liftable head is elevated to position of Figs. 1 and 2, the panel 3 is replaced, and the table is now ready and available for use in wrapping the bundles, and means are provided within 50 the housing 7 of the liftable head for insuring ready access to the free ends of the paper sheets, by the wrapper. A pair of gravity rollers or rolls 21 and 22 are illustrated within the housing in Figure 2, each 55 having a central shaft 23 forming trunnions

at its ends, and if desired small rollers 24 may be utilized on the ends of these trunnions to reduce friction and insure smooth movement of these gravity rolls. The rolls are supported in a pair of side plates 25 attached at the inner sides of the ends of the housing 7, and the plates are provided with complementary pairs of bearing slots 26, 27. These slots are inclined downwardly and to the rear of the machine, and the 70 rollers 24, or the trunnions 23 if rollers are not used, are adapted to ride up and down in these slots. In combination with a stationary roll or rod 28 for each gravity roller, these members are designed to retain the free ends of the paper sheets pulled from the paper rolls 29 and 30 supported beneath the table in a bracket 31 which is provided with the usual supporting members. 75

There are two rolls of paper shown in the drawings, but it will be understood that additional rolls may be used or only a single roll used, and the paper of the rolls is usually of various widths adapting the paper for 80 different sizes of packages or bundles of laundry. The free ends of the paper rolls are brought up through a slot S provided therefor between the rear edge of the panel 3 and the rear wall of the opening 4 in the 85 table top, and then the ends of the paper sheets are passed between the complementary rollers or gravity rolls 21 and 22 and their respective stationary guides 28. The front edges of the paper sheets, as in Figure 90 2 are located at the front of the housing 7 where they are readily accessible to the person wrapping the bundles of laundry. For wrapping a bundle, as indicated in dotted lines in Figure 2, a sheet of paper of required length is pulled from the housing, 95 the paper sheet passing through between the gravity roll 21 and its guide 28. As the paper is pulled out, the pressure on the gravity roll causes said roll to ride up the wall 100 of its slot 26, and the required length of paper is then cut or severed by a cutter designated as a whole by the number 32. While the paper is being severed the gravity roll 21 is in forward, elevated position, but 105 as soon as the paper is severed, the roll 21 is freed and immediately rolls down the incline 26 and pinches the paper sheet against the stationary abutment or bar 28, thus holding the sheet of paper with its free end accessible for a subsequent wrapping operation. The gravity roll is thus pulled by force exerted through the sheet of paper and the paper is released. A stop may be provided if necessary to limit the movement of 110 the gravity roll on its forward movement, but usually the operator readily acquires dexterity so that the pull exerted on the roll is sufficient to release the paper, and then by bearing down on the paper sheet, the for- 115 120 125 130

ward movement of the roll ceases, while the roll is caused to revolve or rotate until the required length of paper is pulled from the liftable head. When the paper is severed 5 the roll then returns to position by action of gravity. If necessary, the roll 22 may be provided with a longer slot 27 to permit greater movement of the roll and insure a longer stretch of paper from the roll 22 10 toward the front of the housing to render the paper sheet accessible. By thus pinching the paper between the gravity roll and the stationary abutment, the paper sheet is maintained in comparatively taut condition 15 to prevent sagging, and the paper is held at its free end in position easy of access for the wrapper.

The required length of paper for wrapping the bundle is severed by the cutter 32, 20 which is adapted to travel horizontally across the front of the housing, and is pushed by hand. The cutter operates in either direction, that is it may be pushed to the right in Figure 1 to sever a sheet, and then 25 pushed to the left to sever the next sheet, and is guided in its movements in the hollow bar or support 33. The cutter support may be of suitable construction, and is suspended at the ends between the legs 8 of the liftable head. A device rectangular in cross section is illustrated as the guide bar for the cutter, but it will be apparent that other forms of guides, as for instance a circular pipe may be substituted if desired.

30 The cutter comprises a slide block 34, preferably of metal, which is fashioned with side tongues 35 adapted to travel in the guide grooves 36 of the guide bar. A pair of knife blades 37 and 38 are carried by the 35 slide block, which blades are made up of sheet metal plates of somewhat triangular shape having inclined, sharpened upper edges. The blades are arranged longitudinally of the slide block or carrier and central thereof with their inclined or sharpened upper edges declining toward the respective ends of the slide block. Mortises 39 are provided in the block for these knife blades and they are fashioned to receive complementary wedges 40, secured in the block by 40 screws 41. Thus by means of the wedges the knife blades are clamped in the slide block and as the latter is pushed by hand, either to right or left in the guide bar, the 45 paper is severed into sheets. A handle 42 is provided for facile manipulation of the cutter, and is secured in the block by screw 43 which passes through a collar 44 on the screw interposed between the handle and the 50 top of the block. A double-end guard 45, of metal plate is clamped between the handle and collar, with its opposite ends turned upwardly to act as guides for the paper and guards for the knife blades as the cutter 55 is operated.

The cutter is pushed back and forth across the front of the housing, guided in the guide bar 33, with each cutting operation and the required length of paper is thus severed from the sheets pulled from the paper rolls. 70

In Figure 2 a length of paper is illustrated as having been severed from the paper sheet. As the free end of the sheet is pulled from its gravity roll it is brought down over the top edge of the guidebar 33, and while held 75 in close contact with the bar by one hand, the other hand is utilized to operate the cutter. The cutter is brought to the edge of the paper and the edge is guided up over the cutting edge of the knife blade, under 80 the guard 45, and then the cutter is pushed to right or left, as the case may be, slitting or severing the sheet of paper as indicated. After the required length of paper has been 85 severed it is wrapped about the bundle of laundry, the completed package is laid aside, and a successive bundle is then wrapped, until all the bundles on the sorting table have been wrapped. After this operation, the panel 3 is removed, the liftable head is 90 lowered into place flush with the table top, and the sorting operation is resumed.

As before stated changes and alterations are contemplated in the construction illustrated, as for instance more than two rolls of paper may be used, or only one roll may be utilized, but in all cases each roll of paper is equipped with a retaining device for the free end of its sheet, the gravity roll being of sufficient weight to insure the return of 100 the roll to its lowered position to pinch the paper against its abutment and retain it in position. The abutment may be a roller with a stationary bearings support, or a fixed bar or rod extending lengthwise of the liftable head. Different sizes and shapes of the elements constituting the machine may be adopted, as well as different materials may be substituted for those illustrated or described, but all such changes or rearrangements fall within the scope of my appended 105 claims.

Having thus fully described my invention, what I claim as new and desire to secure by Letters Patent is:—

1. The combination with a table having a top opening, of a panel adapted to normally close said opening, means for elevating said panel from its normal position, a removable panel closing said opening when the first panel is elevated and forming a slot in the table top, a paper roll supported beneath the table top with its paper sheet passed upwardly through said slot, and gravity actuated means on the elevated panel 120 for retaining the cut free end of said paper sheet.

2. The combination of an open top table, a panel adapted to normally close said open top, means for elevating said panel, a re- 125

movable panel adapted to close the open top and form a paper-guide slot therein, a paper roll below said table top, spaced guides in the first panel having inclined slots, a fixed abutment, and a pinching roll having trunnions in said guide slots, whereby the free end of a paper sheet from said roll is retained.

3. The combination with a table top having an opening and a removable panel, a

liftable panel and operating means therefor, of a cutter supported on the liftable panel, a paper roll supported below said table top, the paper of said roll passing through a slot between the table and the removable panel, and means located within the liftable panel for retaining the free end of said paper roll.

In testimony whereof I have affixed my signature.

WILLIAM B. MUNN.
